UNITED STATES PATENT OFFICE.

EMILE J. GUAY, OF SWAMPSOOTT, MASSACHUSETTS, ASSIGNOR TO GENERAL ELECTRIC COMPANY, A CORPORATION OF NEW YORK.

ARC-LAMP.

1,142,251.

Specification of Letters Patent. Patented June 8, 1915.

Application filed October 25, 1912. Serial No. 727,730.

To all whom it may concern:

Be it known that I, EMILE J. GUAY, a citizen of the United States, residing at Swampscott, in the county of Essex, State of Massachusetts, have invented certain new and useful Improvements in Arc-Lamps, of which the following is a specification.

My invention has reference to an arc lamp, and more particularly to an inclosed arc lamp of the flaming or luminous type.

In accordance with my invention a novel arc inclosure is provided, which is simple and efficient, comprising passages leading from and to the globe through which the products of combustion pass and where they may deposit before they come in contact with the inclosing globe.

For a fuller understanding of my invention, reference is had to the accompanying drawings, in which—

Figure 1 is a vertical section of an arc lamp embodying my invention; Fig. 2 is a side elevation at right angles to Fig. 1, showing parts of the lamp in section and other parts broken away and still other portions of the lamp omitted altogether in order to more clearly illustrate my invention; and Fig. 3 is a sectional plan view on the line 3—3, Fig. 1.

In the drawings, referring first particularly to Fig. 1, 1 is the canopy of the lamp provided with up-standing lugs 2, from which the lamp is supported by a usual form of insulated pulley 3. The canopy is provided with a downwardly extending peripheral flange 4, within which a suitable casing for the lamp may be received. A short cylindrical plate 5 is provided with an outwardly extending flange 6 at its top, by which the plate is secured to the under side of the canopy 1. The bottom of this plate is provided with an inwardly extending annular flange 7, on which is supported a top plate 8. Two tubes 9 are suspended from the plate 8 and register with openings therein. I have here shown the tubes and plate 8 as integral, but it is obvious that the tubes may be secured to the plate in any suitable manner. The lower ends of the tubes 9 communicate with a drum 10, which is closed at the top at 11. A cylindrical sleeve 12 which is enlarged at its bottom to form an economizer 13 for the arc surrounds the upper electrode and is located within and substantially coextensive with

the drum 10. This cylindrical sleeve is secured to the top plate 11 of the drum by suitable lugs and screws 14. An annular partition 15 divides the space between the cylindrical portion of the drum 10 and the sleeve 12 into two annular passages. Transverse partitions 16 are also provided for the tubes 9, which are secured to ears 15^a with which the partition 15 is provided, the partitions of the tubes thus being substantially in alinement with the annular partition 15. These partitions terminate at a point not far from the upper ends of the tubes, preferably a little short of the upper ends, whereby the two passages formed by the partition in a given tube are in free communication with each other at the upper ends of the tubes as well as within the chamber A formed by the canopy 1 and the plate 5 and the top plate 8 through which the tubes 9 pass. The chamber A is preferably divided into two parts by a vertical partition B. An annular plate 16^a having its lower end inclined inwardly to fit snugly about the partition 15 is supported by an inwardly turned flange at the top which engages an outwardly turned flange on the bottoms of the partitions 16. This plate 16^a is formed to deflect the downwardly flowing current of gases in the outer sections of the tubes outwardly against the cool walls of the tubes 9, thereby promoting a rapid circulation of the gases in the tubes and the inclosing globe, which tends to prevent deposit of the fumes on the globe. It will also be observed that an air space is formed between the partition 15 and the plate 16^a, which tends to prevent radiation from the partition and thereby promote the rapid circulation of gases by increasing the temperature difference between the gases in the outer and inner sections of the drum and tubes. A light-transmitting globe 17 is seated at the top against a plate 18 supported and insulated from the drum 10. The opening at the bottom of the globe is closed by a plate 19 having an upturned inwardly flaring sleeve snugly surrounding the lower electrode. The plate 19 is in turn supported from an annular ring 20 carried by arms 21, the outer ends of which are provided with sleeves 21^a by which the globe seat is secured to two sleeves 22 passing through and secured to the drum 10.

The lower and upper electrodes are repre-

110

sented by the reference numerals 23 and 24, respectively. The lower electrode is received in a suitable electrode holder 25, which is carried by two arms 26 and 27, the former of which is secured to a rod 28 extending upwardly through one of the sleeves 22. The outer end of the arm 27 is free but passes through a slot 29 in the sleeve 22, as does the sleeve 26, by which the arms are 10 guided in the usual manner. The upper electrode is received within a carbon-holder 30 secured to a weight 31, which is guided in its movement by two stationary rods 32. One end of a chain 33, which passes 15 over a pulley 34, is connected to the weight 31, while the other end is connected to the rod 28. The electrodes are thus connected together in such a manner as to focus the arc, as is well understood. The pulley 34 is 20 journaled at 35 in a bracket 36.

The operating mechanism for the lamp comprises a magnet 37, whose armature 38 is connected by means of an arm 39 to the outer end of a lever 40, the inner end of 25 which is pivoted at 41. A clutch 42 is supported from the lever 40 and embraces the chain 33. The details of this clutch mechanism are described in application, Serial No. 638,798 which was filed by John T. 30 Beechlyn, July 17, 1911, and I have not deemed it necessary to show the detailed structure of the clutch in this application. The clutch, however, grips the chain when the lever 40 is lifted, and thus separates the 35 electrodes, and when the bottom of the clutch engages the tripping platform 43, the clutch is disengaged from the chain. The leading-in wires are represented by the reference numerals 44 and 45. The lead 44 is connected to the coil 37, the other terminal of 40 which is connected by a conductor 46 to the upper electrode 24. The lower electrode is electrically connected to the frame of the lamp, which is in turn connected to the 45 leading-in wire 45.

The operation of the lamp is very simple and is as follows: When current is turned on, the lamp magnet 37 is energized, thereby attracting the armature 38 and lifting the 50 lever 40. The clutch member 42 is lifted and grips the chain 33 to lift the upper electrode and permit the lower electrode to descend. The electrodes are thus separated to establish the arc, which burns until such 55 time as the clutch descends into engagement with the tripping platform 43, when the chain is released and the electrodes permitted to approach each other. The gases evolved from the arc ascend within the inner annular opening formed between the partition 15 and the economizer 13, and from this annular opening ascend through the inner portions of the tubes 9 to the chamber A at the top of the lamp, from whence 60 they descend in the outer portions of the

tubes 9 on the outside of the partition 16 and into the annular opening formed between the periphery of the drum 10 and the partition 15, where they again pass into the globe adjacent the wall of the globe. A 70 recurrent circulation is thus produced within the lamp and the solidifiable products of combustion are deposited within the drum and the partition to the same and within the tubes and the chamber at the top of the 75 tubes.

It will be seen that my invention provides a simple and efficient inclosure within which the fumes from the arc are deposited where they do not obscure the light, and from 80 which they may readily be removed.

What I claim as new and desire to secure by Letters Patent of the United States is:—

1. In an arc lamp, an arc inclosure comprising a transparent or translucent globe 85 open at the top within which the arc is formed, a drum closed at the top surmounting and communicating with the globe, and one or more tubes closed at the top surmounting and communicating with the 90 drum, the drum having an annular partition and the tubes having vertical partitions substantially in alinement with the upper edge of the annular partition, the tube partitions terminating short of the upper ends of the 95 tubes, whereby circulatory passages are formed from and to the globe.

2. In an arc lamp, a substantially air-tight 100 arc inclosure comprising a light transmitting globe open at the top within which the arc is formed, a drum closed at the top surmounting the globe and communicating therewith, one or more tubes closed at the top surmounting the drum and communicating therewith, the drum being provided with 105 an annular partition extending throughout its length and the tube or tubes being provided with partitions which are substantially continuous with the partition of the drum and terminating at a point short of 110 the ends of the tubes, whereby circulatory passages are formed to and from the globe.

3. In an arc lamp, a substantially air-tight 115 inclosure comprising a light transmitting globe within which the arc is formed, a drum closed at the top surmounting and communicating with the globe, a circular partition for the drum extending substantially from the top of the globe to the top 120 of the drum, one or more tubes closed at the top surmounting and communicating with the drum, and partitions for said tubes substantially in alinement with the partition of the drum, and terminating short of the tops 125 of the tubes, whereby circulatory passages are formed from and to the globe which open at a point substantially in the plane of the top of the globe.

4. In an arc lamp, a globe within which 130 the arc is formed, a drum closed at the top

- surmounting and communicating with the globe, a sleeve surrounding the upper electrode, a vertical annular partition for the drum, one or more tubes closed at the top 5 ascending from and communicating with the drum, partitions for the tubes continuous with the partition for the drum and terminating short of the ends of the tubes, and depositing chambers formed at the tops of 10 the tubes and communicating with said tubes, whereby circulatory passages comprising two annular openings formed in the drum and having their orifices substantially in a plane with the top of the globe are 15 formed to and from the globe.
5. In an arc lamp, a pair of electrodes, a substantially air-tight arc inclosure comprising a transparent or translucent globe, a drum surmounting and communicating 20 with said globe, a partition for said drum and an envelop located above the drum having passages communicating with the respective passages formed by the drum and

its partition, and means for deflecting the gases descending between said partition and 25 said drum outwardly against the walls of the drum.

6. In an arc lamp, a pair of electrodes, a substantially air-tight arc inclosure comprising a transparent or translucent globe, a 30 drum surmounting and communicating with said globe, a partition for said drum and an envelop located above the drum and having passages communicating with the respective 35 passages formed by the drum and its partition, and an annular plate surrounding the partition formed so as to deflect the descending gases outwardly and to leave an air space between said plate and said partition.

In witness whereof, I have hereunto set 40 my hand this 23rd day of October 1912.

EMILE J. GUAY.
